UNITED STATES PATENT OFFICE.

FRANK DUTCHER, OF VERSAILLES, PENNSYLVANIA, ASSIGNOR TO CENTRAL RAILWAY SIGNAL COMPANY, OF PITTSBURGH, PENNSYLVANIA.

RAILWAY SIGNAL-TORPEDO.

1,284,621.

Specification of Letters Patent.

Patented Nov. 12, 1918.

Application filed February 15, 1918. Serial No. 217,374.

To all whom it may concern:

Be it known that I, FRANK DUTCHER, a citizen of the United States, residing at Versailles, in the county of Allegheny and State 5 of Pennsylvania, have invented certain new and useful Improvements in Railway Signal-Torpedoes, of which the following is a specification, reference being had therein to the accompanying drawing.

10 This invention relates to improvements in railway signal torpedoes and the object of the invention is to provide a simple, cheap and efficient signal torpedo for use on railways.

15 In general terms the present invention comprises a flattened paper tube; a flat clip (preferably metal) fitting within the bottom of the tube and attached thereto by suitable ears or projections; an explosive tablet of a 20 flat rectangular shape, and a sheet of paper wrapped around the tablet and cemented, the ends of the paper doubled back over the tablet and overlapping each other, the wrapped tablet fitting within the flattened 25 paper case and a means for attaching the torpedo to the head of a railroad rail.

In the accompanying drawings,

Figure 1, is an inverted perspective view of a torpedo embodying my invention.

30 Fig. 2, is a detached perspective view showing the parts of my improved torpedo in separated relation.

Fig. 3, is an enlarged central, vertical sectional view of my torpedo, the wrapping for 35 the explosive being exaggerated for the purpose of bringing out more clearly its construction when folded and placed within the flattened paper case.

Fig. 4, is a perspective view showing the 40 wrapper containing the explosive tablet, and with the ends of the wrapper extended before they are folded and lapped over.

Fig. 5, is a plain view of the sheet or wrapper in which the tablet is wrapped.

45 Figs. 1, 2, 4 and 5 are substantially full size views of a torpedo made in accordance with my invention, except that the extended ends of Fig. 4 are thicker than the full size part there represented, and made so for the 50 purpose of bringing out more clearly the several layers of the sheet when doubled as shown in that figure.

Referring now particularly to the draw-

ings, 1 is a fiber tube preferably of paper. This tube is flattened and is of rectangular 55 shape and approximately square.

The tube 1, is rolled in the ordinary manner from a sheet of paper and is preferably rolled in circular shape after which it is flattened in any suitable manner. The tube being rolled from a sheet of paper, there is a lapping edge and the tube is so flattened that this overlapping edge preferably appears at or approximately at the center of the bottom of the tube as at 2. 60 65

A flat clip 3, is provided and this clip is preferably formed of sheet tin. It is provided with projecting ears 4, on its corners and with two transversely extending slots 5 between its ends which are located on a central line drawn longitudinal to the clip. A lead strap is provided for holding the torpedo to the head of a railroad rail in a manner well understood by those skilled in this art. This strap 6 is threaded through 70 the openings 5 of the clip preferably in the manner shown in Fig. 2. The clip is then placed within the flattened tube 1, and the ears 4 are turned around under and against the outer side of the bottom of the tube 1 75 80 as clearly shown in Figs. 1 and 3.

This clip serves several purposes, among which are that it provides an efficient means for attaching the lead strap to the torpedo in a manner to prevent it from becoming detached and it strengthens and gives stability 85 to the torpedo. The ears 4, which clamp the bottom of the tube 1, as shown, serve as a means to prevent the paper forming the tube from becoming unwrapped under the 90 influence of moisture or water.

An explosive tablet 7, is provided and this tablet is wrapped in a sheet 8. This sheet 8 is shown extended in Fig. 5, and the dotted lines 9 shown in this figure indicate where 95 the sheet folds when the tablet is wrapped therein, and the dots 10 indicate a waterproof cement which is applied to the sheet. The cement is applied so as to leave an uncemented space at one end of the sheet with 100 the cement extending at each side of the space as shown at 11. The explosive tablet 7, is of a size corresponding to the space 12, and it is placed thereon, and the tablet is wrapped therein by rolling it up in the 105 sheet which folds the sheet on the dotted

lines 9. It will be observed that the cement portions 11, serve to cement the sheet as it is rolled and to tightly close the wrapped ends 13. The object of leaving the un cemented space at one end of the sheet is to prevent any of the cement coming in contact with the explosive tablet, because the tablet quickly absorbs moisture from the cement, and this is objectional because moisture is injurious to an explosive. The tablet being rolled within the sheet 8, on the lines 9, the result of such wrapping is the package as illustrated in Fig. 4. The ends 13 are then doubled over the body of the package and lapped as shown in Figs. 2 and 3. When the ends are folded as described they double at the points 14, (Fig. 4) and the result is that the explosive tablet is completely and tightly wrapped and inclosed within the sheet 8. The package containing the explosive tablet may be dipped in water-proof material when it is in the form shown in Fig. 4, and the tablet is thus inclosed within a water-proof wrapping, or the outer side of the sheet 8 may be water-proof in any suitable manner before the tablet is wrapped.

With the tablet package 15 in the form shown in Fig. 2, it is pushed within the tube 1, in the position shown in Figs. 1 and 3 with the clip 3, below it.

I find from actual practice and actual test that with a torpedo of this construction no metal part whatever flies when it is exploded. With the ears 4, double around the outer side of the case 1, the explosion does not have any tendency to, and does not blow them out or disturb their position.

It will also be observed that the lapped ends 13, form a cushion between the explosive 7, and the metal parts of the torpedo. While it is not essential to have the lapped over ends at the bottom of the torpedo it is preferred to have them so located. However, the tablet package can be placed within tube 1, with the double over ends either on its top or its bottom, in either case the wrapping around the tablet will form a cushion between the explosive tablet and the metal clip and strap.

Having thus described my invention what I claim and desire to secure by Letters Patent is:

1. A railway signal torpedo, comprising a fiber tube, an explosive, a wrapping for the explosive, a strap attaching clip within the tube, a wrapped explosive placed within the tube with the wrapping between the explosive and the clip.

2. A railway signal torpedo, comprising a fiber tube, a metal clip within the tube and having attaching ears extending outside of and clamped down on the outer side of the tube, an explosive and a wrapping for the explosive, a wrapped explosive placed with

in the tube with the wrapping between the clip and the explosive.

3. A railway signal torpedo, comprising a fiber tube, a metal clip within the tube and attached thereto, an explosive, a paper wrapping for the explosive, the wrapping extending beyond the explosive and is doubled backward on the body of the explosive forming an explosive package, said package placed within the tube with the wrapping between the explosive and the clip. 70 75

4. A railway signal torpedo, comprising a flat rectangular fiber tube, a flat strap attaching clip within the tube and a rectangular flat explosive tablet, a wrapping for the tablet, the wrapped tablet placed within the tube with the wrapping between the explosive and the clip. 80

5. A railway signal torpedo, comprising a rectangular flat fiber tube, a flat metallic strap attaching clip within the flat tube, a flat explosive tablet having a paper inclosure forming a tablet package, said package placed within the tube. 85

6. A railway signal torpedo, comprising a flat rectangular fiber tube, a flat metallic strap attaching clip within the tube and attached to one wall thereof, a rectangular flat explosive tablet, a water-proof inclosure for the tablet making a water-proof tablet package, said package placed within the tube 90 with its water tight inclosure between the explosive and the said clip. 95

7. A railway signal torpedo, comprising a rectangular flat fiber tube, a metallic flat strap attaching clip within the tube, a rectangular flat explosive tablet, an inclosure for the explosive tablet having its ends lapped on the body of the tablet, constituting a tablet package, said package placed within the tube with the doubled over ends 100 105 of the inclosure between the explosive and the said clip.

8. A railway signal torpedo, comprising a rectangular flat fiber tube, a metallic attaching clip fitting within the tube, said clip having a strap attaching opening, a strap threaded through said opening with its ends projecting beyond the ends of the tube, and an inclosed flat explosive tablet within the said tube. 110 115

9. A railway signal torpedo, comprising a rectangular flat fiber tube, a strap attaching clip having a strap opening, the ends of the clip having ears projecting and clamping down the outside of the tube, and a flat explosive tablet inclosed within a paper closure, said inclosed tablet placed within the tube. 120

10. A railway signal torpedo, comprising a rectangular flat fiber tube, an explosive package comprising a rectangular flat explosive tablet wrapped within a sheet, the sheet projecting beyond the ends of the tab- 125

let and the ends of the wrapped sheet double back on the body of the tablet, the said package placed within the tube, and a rail attaching strap connected to the tube.

- 5 11. An explosive package for railway signal torpedoes, comprising a rectangular flat explosive tablet, a paper sheet wider and longer than the tablet, said sheet having its inner side cemented to leave an uncemented
10 space larger than the tablet for the purpose described, the tablet placed in the unce-

mented portion of the sheet and the sheet wrapped around the tablet with the extended ends of the sheet double inward on the body of the tablet.

15

In testimony whereof I hereunto affix my signature in the presence of two witnesses.

FRANK DUTCHER.
